E. J. PFEIFFER

FOOT ACCELERATOR

Filed Nov. 3, 1923

Patented July 8, 1924.

1,500,889

UNITED STATES PATENT OFFICE.

ELI J. PFEIFFER, OF UNION GROVE, WISCONSIN.

FOOT ACCELERATOR.

Application filed November 3, 1923. Serial No. 672,647.

To all whom it may concern:

Be it known that I, ELI J. PFEIFFER, a citizen of the United States, residing at Union Grove, in the county of Racine and 5 State of Wisconsin, have invented new and useful Improvements in Foot Accelerators, of which the following is a specification.

This invention relates to new and useful improvements in foot accelerators and more 10 particularly to a foot accelerator for a Fordson motor. The main object of the present invention being the provision of a foot accelerator which can be quickly and readily attached to a tractor of the Fordson type and arranged in a convenient position 15 for the driver of the vehicle so as to eliminate the necessity of the driver using his hands for actuating the throttle of the motor to control the speed of the same.

Another object of my invention is the 20 provision of a foot accelerator particularly adapted for Fordson tractors which can be quickly and readily applied to the designs of tractors in use at the present time without necessitating any change of the parts of 25 the tractor and includes means for readily connecting the same to the carburetor and the ordinary hand control of the tractor.

With the above and other objects in view 30 the invention consists in the novel features in construction, the combination and arrangement of parts hereinafter more fully set forth, pointed out in the claims and shown in the accompanying drawings in 35 which:

Fig. 1 is a side elevation illustrating the application of my improved accelerator, portions of the tractor being shown in outline.

Fig. 2 is an enlarged side elevation of the device.

Fig. 3 is a section taken on the line 3—3 of Fig. 2.

Fig. 4 is a section taken on the line 4—4 of Fig. 2.

Referring now more particularly to the drawings, in which reference characters are used to designate the several parts throughout the views, the numeral 1 indicates in 50 general a bracket which supports the foot pedal 2. The bracket includes the arms 3 and 4 provided at their outer ends with suitable bolt openings 5 whereby they may be readily connected to the side of the gear 55 shifting plate as shown in Fig. 1. The ends of the arms 3 and 4 are brought to-

gether and disposed in alignment with an opening extending therethrough to receive a pivot bolt 6. The foot pedal 2 is provided with a perforated ear 7 disposed in 60 alignment with the ends of the arms 3 and 4 of the bracket and through which the pivot pin 6 extends for pivotally mounting the foot piece upon the bracket.

The main actuating rod 8 of my improved device is mounted for rotating movement within the supporting sleeves 9, one of said sleeves being preferably secured to the bracket 10 which supports the gasoline supply tank of the tractor. The other sleeve is 70 preferably secured to one of the bolts which secures the cover on the differential case as illustrated in Fig. 1 so that these two sleeves may be arranged in substantially spaced relation. The lower end of the rod 8 is provided with a crank arm 11 and pivotally connected to one end of the crank arm is a link 12, the other end of which is pivotally connected at 13 to the outer end of the toe portion of the foot pedal 2. From this construction it will be readily apparent that when the toe portion of the foot pedal 2 is 75 pressed downwardly the crank 11 will be actuated to impart a rotary movement to the rod 8.

A sleeve 14 is mounted upon the upper end of the rod 8 and connected thereto, said sleeve having extending outwardly therefrom an arm 15 provided at its outer end with a plate 16. This plate 16 has loose connection with an eye formed upon one end of the connecting rod 17 which is fastened to the carburetor control rod 18. The end of the rod 17 which connects with the control rod 18 may be secured in any suitable manner, but preferably by forming a sleeve upon the end of the rod 17 which embraces the rod 18 and is secured thereto through the medium of a set screw or the like. From this construction it will be apparent that when movement is imparted to the foot pedal 2, the rod 8 will be rotated for actuating the arm 15 which in turn will impart a pulling movement to the rod 17 for actuating the control rod 18.

In order to provide means for connecting the foot actuating device with the main throttle 19 a rod 20 is connected at one end to the handle throttle 19 and extends downwardly to the looped connection between the rods 15 and 17 and loosely engages with the plate 16 on the rod 15 as shown in Figs. 1 to

3. As a general rule the hand throttle movement on a Fordson tractor is in an inclined plane and from the construction illustrated and set forth in the drawing, it will be noted that when the rod 8 is rotated the movement of the arm 15 will have a tendency to pull downwardly upon the rod 20 and actuate the hand throttle 19 and from this it will be apparent that the accelerator rod 18 may be readily controlled from either the foot pedal 2 or the hand throttle 19.

In order to return the rod 18 in a direction opposite to that in which it is moved by the hand throttle 19 or foot pedal 2 or in other words to close the carburetor a spring 21 is connected at one end to the plate 16 of the arm 15 with its other end connected to any suitable part of the machine so that the spring will be disposed in a position to exert tension for pulling against the movement of the arm 15 so that after the foot pedal 2 or hand throttle 19 have been released from active movement, the tension of the spring 21 will move the rod 18 to close the carburetor.

It will be apparent from the above description taken in connection with the drawings that I have provided an extremely simple device which can be quickly and readily attached to Fordson tractors in use at the present time and wherein the speed of the same may be readily controlled by the foot of the operator so that the operator's hands may be free for use entirely in steering the vehicle. It will also be apparent that the device can be quickly and readily assembled and applied to the tractors in use at the present time.

40 While I have shown and described the preferred form of my invention I wish it to

be understood that various changes and alterations may be carried out during the manufacture of the same without departing from the spirit of the invention or the scope 45 of the appended claims.

Having thus described my invention what I claim is:

1. An accelerating device including a rotatable rod, a crank arm at one end of the 50 rod, a pivoted foot treadle having connection with the crank arm, a connecting arm at the other end of the rod, a connecting rod having loose connection with the outer end of the connecting arm, a second connecting rod loosely connected with the arm at one end and having its other end connected with the hand throttle of a motor, said first rod having connection with the accelerator rod of a motor, and a spring 60 member having one end connected to a stationary part of the motor and the other end attached to the loose connection between the arm and the aforesaid rods.

2. The combination with a motor, having 65 an accelerator rod, and a hand throttle for actuating said rod, of an auxiliary rod disposed at an oblique angle with respect to the accelerator rod and mounted for rotary movement, a crank upon one end of the rod, 70 a foot treadle having connection with the crank for imparting movement to the rod, means forming connection between the accelerator rod and the first rod, additional means forming connection between the first 75 rod and the handle throttle, and a spring having connection with the aforesaid means and a stationary portion of the motor.

In testimony whereof I affix my signature.

ELI J. PFEIFFER.
